UNITED STATES PATENT OFFICE.

JACOB B. ROHRER, OF WASHINGTON, DISTRICT OF COLUMBIA.

UMBRELLA.

SPECIFICATION forming part of Letters Patent No. 748,655, dated January 5, 1904.

Application filed March 3, 1903. Serial No. 146,004. (No model.)

To all whom it may concern:

Be it known that I, JACOB B. ROHRER, a citizen of the United States, residing at Washington, in the District of Columbia, have invented a new and useful Umbrella, of which the following is a specification.

My invention relates to umbrellas; and it consists in the improved construction herein-after described and claimed, and shown in the accompanying drawings, forming a part of this specification.

A common defect in umbrellas as ordinarily constructed is the breaking of the umbrella-stick just beyond the point of attachment of the cover structure to the stick. When such a break occurs, it is necessary to replace the broken stick with a new one, which is a matter of considerable difficulty, or to discard the umbrella.

The object of this invention is to provide a simple, practical, and effective means for repairing umbrellas broken in the manner above explained, so that the necessity of replacing the broken stick with a new one may be obviated.

A further object of the invention is to provide means for repairing sticks broken, as above specified, in such a manner that the umbrella so repaired will be stronger and better adapted to resist breaking than before the break occurred.

Referring to the drawings, in which corresponding parts are designated by the same characters of reference throughout the various views, Figure 1 is a view in side elevation of the downward end of an umbrella-stick provided with associated structures constructed in accordance with my invention. Fig. 2 is a view, partly in elevation and partly in section, of a broken umbrella-stick repaired by means of my invention with the associated members of an umbrella-frame attached thereto. Fig. 3 is a view showing the tubular member 2, Fig. 1, in longitudinal section and the umbrella-stick in elevation, the position of the parts in all of the first three figures being the reverse of that assumed when the umbrella is carried in closed condition. Fig. 4 is a detail view showing an umbrella-stick provided with a runner constructed in accordance with my invention. Fig. 5 is a de-

tail showing the construction of the cover-protector and a portion of the member 2 designed to coöperate therein. Fig. 6 is a detail view showing the rib and stretcher joined. Fig. 7 is a detail showing the construction of the runner and means for fastening the stretchers thereto.

In the above-mentioned figures, 1 designates an umbrella-stick, and 2 is a tubular member which may be applied to the stick when the umbrella is manufactured, as shown in Fig. 1, in which case it forms a reinforce for the stick and effectively prevents breakage at the point above mentioned, or which may be applied, as shown in Fig. 2, to a broken umbrella-stick to form an extension thereof and make the replacement of the broken stick unnecessary.

3 represents a plug mounted in the end of the tubular member 2 when used as an extension, as shown in Fig. 2. The plug 3 extends into the tubular member 2 until its lower end abuts against the broken end of an umbrella-stick 1, thus preventing the umbrella-stick from being forced farther into the tubular member 2 when used as a cane. The plug 3 is removably held in position by means of a pin 4, which passes through a slot 5, provided near the upper end of the tubular member 2, and extends into the plug 3. The tubular member 2 may be tapered externally, as shown in Fig. 3, or provided with a shoulder, as shown in Fig. 2, to form a seat for an annular "notch" member 6, grooved on its upper surface, as shown at 7, and provided with notches terminating in rounded sockets 8, in which fit the rounded ends 9 of the ribs 10. The groove 7 is of sufficient depth for the rounded ends 9 of the ribs to rest in their sockets without projecting beyond the upper margin of the annular member 7. The ends of the ribs are retained in their sockets by means of another annular member 11, which is flat on the surface adapted to contact with the member 6. At diametrically opposite points on the portion of the tubular member 2 above the seat for the annular member 6 are provided two longitudinal projections or ribs 12, which terminate slightly above the notch. Grooves or slots 13 are provided at suitable points on the inner margin of the annular member 11 to permit

the passage of the ribs 12 as said annular member is moved into position to hold the ribs in their sockets in the member 6. In order to hold the member 11 in operative position, the cover-protector 14 is made, as shown, with grooves 15 to permit the passage of the ribs 12, and with the inclined surfaces 16, which may be made to engage with the ends of the ribs 12 after the cover-protector 14 has been forced into close contact with the cover, where it is secured to the member 2 by simply rotating said cover-protector in the direction indicated by the arrow in Fig. 5. When the cam-surfaces 16 are brought into engagement with the ends of the ribs 12 in the manner explained, the cover-protector 14 is forced into firm engagement with the cover 17 and that is pressed against the member 11 so strongly that said member 11 is held in close contact with the member 6 and effectively retains the ribs in their sockets.

In order to prevent rotation of the runner upon the umbrella-stick, slots 18 18, extending longitudinally of the stick 1 for a suitable distance, are provided, and the runner 19 is provided with lugs or projections 20, which engage the slots 18 and prevent rotation of the runner on the stick, while in no way interfering with its sliding movement thereon. The runner 19 is constructed in similar fashion to the notch described in the preceding paragraph, and consists of a tubular portion 21 and an annular flange 22, rigidly secured on said tubular portion and provided with notches 23 and sockets 24, similar to those provided in the annular member 6 and adapted to receive the rounded ends 25 of the stretchers 26. The said stretchers 26 are retained in their sockets by means of an annular retainer 27, provided with grooves 28 for the passage of lugs 29, suitably located on the tubular portion 21 of the runner and arranged at diametrically opposite points on its surface. The lugs 29 are placed slightly below the annular flange 22 and are adapted to engage with two inclined cam-surfaces 30, provided on the annular retainer 27 to hold it in position to retain the ends of the stretchers in their sockets. The ribs 10 and the stretchers 26 are connected by ball-and-socket joints. On each rib is provided a U-shaped member 31, in each of the free ends of which is provided a depression 32, adapted to receive a rounded end of a stretcher in all respects similar to the end engaging with the runner.

In umbrellas constructed in accordance with my invention, as above explained, the tubular member 2 is fitted on the stick 1, which then extends entirely through the tubular member, and the ordinary ferrule or tip is employed. The member 2 in this case serves as a reinforce to the stick 1 and strengthens the stick at the point where breakage is ordinarily most apt to occur, so that breakage at that point is almost impos-

sible. When the member 2 is to be used for repairing umbrellas whose sticks have become broken just beyond the cover-protector, the notch, cover-protector, cover, and ribs 70 must be detached from the umbrella-stick. The member 2 (which, it is understood, is to be made in different sizes to correspond to the various standard sizes of an umbrella-stick) is then fitted on the end of the broken stick, as shown in Fig. 2, and the plug 3 is inserted into the end of the member 2 until it contacts with the broken end of the stick 1, in which position it is secured by a pin 4, passing through the slot 5, as shown, and so prevents any jamming of the stick 1 farther into the tubular member 2. When used in this way, the member 2 must be so adjusted on the end of the broken stick 1 that the seat for the notch in which the ribs are secured 85 is at the proper position to engage with ribs of the length used in that particular umbrella.

The method of connecting the umbrella-ribs with the notch described above and of securing the parts of the notch in position is peculiarly advantageous, for the reason that the fastening means locks positively by means of the engagement of the cam-surface 16 on the cover-protector 14 with the ends of the ribs 95 12, so that there is no tendency of the cover-protector to become accidentally disengaged, and so permit separation of the various parts held in position by it, but is of such character that whenever it becomes necessary to separate the parts, as when a rib is broken, it is easily accomplished by merely giving the cover-protector 14 a turn through an arc of about ninety degrees, bringing it in position to slide downward over the lower portion of 105 the tubular member 2 and permit the separation of the two members of the notch and removal of the ribs therefrom.

The means for securing the stretchers to the runner is so similar in its operation to 110 the fastening means for the ribs that no explanation of the operation thereof seems necessary, and the action of the slots 18 and the lugs 20 in preventing any rotation of the runner upon the stick 1, and so obviating any 115 entangling or bending of the ribs from such rotation, is also obvious and requires no further explanation.

It should be stated that when the tubular member 2 is to be used in repairing umbrella-sticks of the ordinary type which have become broken just beyond the cover-protector notches of the usual form may be used thereon instead of those of the form described above, as the notch described is adapted only for use 125 with ribs having rounded or ball-like ends adapted to engage with the sockets provided in the notch. When a notch of the ordinary construction is used, it may be secured in position on the tubular member 2 in any desired 130 way, and no special means of attachment is necessary. The cover-protector then em-

ployed may be of the usual form or of the form herein described, as either will be capable of use with the ordinary type of notch.

Having thus described my invention, what 5 I claim as new, and desire to secure by Letters Patent, is—

An extension for broken umbrella-sticks comprising a tubular member adapted to fit snugly over the broken end of the stick, a re- 10 movable plug at its outer end adapted to contact with the broken end of the umbrella-

stick and to prevent said stick from being forced farther into the extension and means to hold said plug in position.

In testimony that I claim the foregoing as 15 my own I have hereto affixed my signature in the presence of two witnesses.

JACOB B. ROHRER.
